LIPSTICK KIT

Ira W. Schwartz, 2 Terrace Drive,
Great Neck, N.Y. 11021

Filed June 16, 1966, Ser. No. 2,693

Term of patent 14 years

(Cl. D86—10)

FIG.1.

FIG.2.

FIG.3.

FIG.4.

FIG.5.

FIG.6.

FIG.7.

FIGURE 1 is a top plan view of the lipstick kit embodying my new design, the lid of said kit being shown in closed position to show the design features of the lid;

FIGURE 4 is a rear elevational view of the lipstick kit, each of the sides being the same; and

FIGURE 5 is a bottom plan view of the lipstick kit; FIGURE 6 is a side elevational view of the lipstick kit, each of the sides being the same; and FIGURE 7 is a perspective view of the lipstick kit, the lid being shown in partial open position, the broken lines representing the ornamentation shown in FIGS. 1 and 2, said ornamentation being omitted for convenience of illustration, also omitted is the showing of the lipstick tubes which can be seen faintly through the sides of the kit.

I claim.

The ornamental design for a lipstick kit, as shown and described.
